MAST SUPPORT

Hugh G. Sesler, Warren, Ohio

Application February 17, 1950, Serial No. 144,723

3 Claims. (Cl. 248—43)

1

My invention relates to mast supports, particularly to supports for television antennas, and the principal object of my invention is to produce new and improved supports of this character.

Proper support of a mast in low-cost manner and with provision for ready maintenance has been a considerable problem for some time. This problem has been accentuated with the advent of television since a large number of localities still require an outside antenna of considerable height.

Heretofore, television antennas have either been installed in costly manner to insure stability, or have been installed in cheap and haphazard manner. The costly installation seriously limited the sale of television apparatus; on the other hand, many communities have considered legislation prohibiting haphazard installations because of the many dangers involved. My invention provides low cost apparatus for supporting a mast, such apparatus being easily installed with the use of only simple tools. Further, through use of my invention, one man may easily install a television antenna, thus reducing labor cost. Also, my invention makes it possible to easily lower the mast, should repairs be necessary.

In the drawing accompanying this specification and forming a part of this application, there is shown, for purposes of illustration, an embodiment which my invention may assume, and in this drawing:

Figure 1 is a perspective view illustrating an embodiment of my invention, and showing such invention as supporting a mast from a roof top,

Figure 2 is an enlarged vertical sectional view taken through the embodiment,

Figure 3 is a side elevational showing, in full lines, the device in upright position, and showing, in dotted lines, the device in horizontal position,

Figure 4 is an enlarged, transverse sectional view corresponding generally to the line 4—4 of Figure 2, and

Figure 5 is a perspective view of a spring clip used in the embodiment disclosed.

My invention provides a mast support comprising means engageable with the mast and supported so that it may be moved to and from upright position, other means being provided to selectively prevent or permit movement of the mast supporting means.

With particular reference to the drawings, wherein is disclosed a presently preferred embodiment of my invention, the mast 10 is supported by a tubular member 11. The mast may be the

2

support for a television antenna, or it may be a flag pole, or it may be used for any one of a number of other applications.

As herein disclosed, a pair of strips 12 and 13 provide the means for supporting the tubular member 11, such strips being preferably disposed at opposite side surfaces of the tubular member 11 and each terminates in a leg 14 for securing to a support, such as a roof or the like. The legs 14 may be bent to fit the shape of any support, and as shown in dot-dash lines, at 14a, one leg is straight with the remainder of the strip, and the other leg is bent at right angles to the remainder of its strip, for installation on a right-angled supporting surface. As shown in full lines in Figure 2, each of the legs 14 is angled so as to conform to the angularity of the peak of a roof, and the legs may be formed with apertures to pass lag screws for attachment to the roof.

10 The tubular member 11 is formed with longitudinally spaced pairs of apertures 15 and 16, each pair of apertures, in the case of a round tube, being preferably diametrically aligned. Each of strips 12 and 13 is formed with apertures 17 and 18 which are longitudinally spaced to correspond to the spacing of the apertures 15 and 16.

15 The tubular member 11 and strips 12 and 13 are assembled by aligning apertures 17 and 18 with respective apertures 15 and 16, and bolts 19 and 20 are passed through the respective aligned apertures, nuts 21 and 22 being threaded on the terminal ends of respective bolts to prevent their displacement.

20 To install a device of my invention, a user secures the legs 14—14 to the support surface, such as the roof, by means of lag screws or the like, the legs having first been bent, if necessary, to follow the angularity of the roof surface. The lower bolt 20 is then removed so that the tubular member 11 may be pivoted about the upper bolt 19, and moved from upright position, shown in full lines in Figure 3, to a horizontal position shown in dot-dash lines.

25 The lower end of the mast 10 may then be inserted into the socket formed by the tubular member 11, inserting movement being limited by abutment of the lower end of the mast with the transversely extending shank portion of the bolt 19. A set-screw 23, carried by the tubular member 11, may be tightened on the mast to prevent movement of the mast in its socket.

30 Assuming that any necessary guy wires have already been attached to the mast in proper location, a user may then elevate the mast by grasping it at a point distant from the pivot and

"walking" the mast to upright position by turning the mast about the pivot formed by the bolt 19 while at the same time moving toward the pivot. It will be appreciated that this is the same action used in "walking" a ladder to upright position.

When the mast 10, together with the tubular member 11, has been moved to upright position, the bolt 20 is inserted through aligned apertures 16 and 18, respectively, in the tubular member 11 and strips 12, 13, and its nut is threaded in place. In this condition, the tubular member 11 and mast 10 are held in upright position and a user may secure the guy wires, if such wires are necessary and are used.

As best seen in Figures 2 and 3, a strip 24 is welded to the exterior surface of the tubular member 11, intermediate the heads of the bolts 19 and 20. The terminal edges of the strip 24 provide abutments which engage the bolt heads 20 and hold the bolts from turning during the time nuts are threaded on the bolts.

To further facilitate installation, spring clips 25 are secured to the lower end of the tubular member 11 in diametrically opposite relation. Each of the spring clips 25 comprises a pair of legs 26, an upper portion of each leg being welded to an interior surface of the lower end of the tubular member, so that lower portions of the legs 26 and a bight portion 27 connecting respective legs 26 extend beyond the lower end of the tubular member 11. The bight portion 27 of each spring-clip 25 is recessed to form a socket for receiving a respective one of the strips 12, 13.

As the tubular member 11 is moved to upright position, and just prior to reaching such position, the spring-clips 25 will engage respective ones of strips 12, 13 and the spring-clips 25 will be cammed inwardly of the tubular member 11 to permit passage of the strips 12, 13. In upright position of the tubular member 11, the recessed bight portion 27 of each spring-clip will snap around a respective strip and thus yieldably hold the tubular member 11 in upright position. It will be appreciated that the spring-clips may be made of sufficient strength so as to hold the mast in upright relation with no further support. However, as presently preferred, the spring-clips 25 are designed to snap around the strips 12, 13 to indicate when upright relation has been reached and to form a support against pivot action during the time a user inserts the bottom bolt 20.

In view of the foregoing, it will be apparent to those skilled in the art that I have accomplished at least the principal object of my invention, and it also will be apparent to those skilled in the art that the embodiment herein described may be variously changed and modified, without departing from the spirit of the invention, and that the invention is capable of uses and has advantages not herein specifically described; hence it will be appreciated that the herein disclosed embodiment is illustrative only, and that my invention is not limited thereto.

I claim:

1. A mast support, comprising: tubular means for supporting the mast; means for supporting said tubular means, comprising a pair of strips disposed on opposite side surfaces of said tubular means and providing legs which are adapted to be secured to a support, such as a roof; a pivot

connection between said strips and said tubular means, whereby said tubular means may be swung to and from upright position; and spring-clip means carried by said tubular means, and having snap engagement with at least one of said strips when said tubular means is in upright position, for yieldably holding said tubular means in upright position.

2. A mast support, comprising: tubular means for supporting the mast; means for supporting said tubular means, comprising a pair of strips disposed on opposite side surfaces of said tubular means and providing legs which are adapted to be secured to a support, such as a roof; first bolt means providing a pivot connection between said supporting means and said tubular means, whereby said tubular means may be swung to and from upright position, said first bolt means forming an abutment limiting the amount the mast may be inserted within said tubular means and forming a support for the weight of the mast when the latter is in upright position; spring-clip means carried by said tubular means and having snap engagement with at least one of said strips when said tubular means is in upright position, for yieldably holding said tubular means in upright position; and second bolt means spaced from said first bolt means for connecting said tubular means and said supporting means against relative movement.

3. A mast support comprising a tubular socket for receiving the lower end of the mast, a pair of separate leg members disposed on opposite sides of said socket to provide clearance for pivotal movement of said socket therebetween, each of said leg members having a depending portion extending beyond the lower end of said socket for attachment to a supporting surface, each of said depending leg member portions being movable to conform to the configuration of said supporting surface, an upper bolt member extending transversely through said socket member and through the upper portion of said leg members to limit inward movement of said mast into said socket member, said upper bolt member also providing a pivot connection between said socket and said leg members for swinging movement of said socket between said leg members to and from substantially horizontal position respectively for inserting a mast into said socket and thereafter for erecting said socket and mast, a lower bolt member insertable transversely into said leg members and through the interposed upright socket below the lower end of said mast to hold said socket and mast in upright position against swinging movement on said leg member, said lower bolt member being removable from said inserted position to again provide for swinging movement of said socket on said upper bolt member for the purposes described.

HUGH G. SESLER.
